UNITED STATES PATENT OFFICE.

EUGENE F. GLOCK, OF DETROIT, MICHIGAN.

EDGE-PROTECTOR FOR CONCRETE.

No. 893,820.

Specification of Letters Patent.

Patented July 14, 1908.

Application filed August 12, 1907. Serial No. 388,140.

To all whom it may concern:

Be it known that I, EUGENE F. GLOCK, a citizen of the United States, residing at Detroit, county of Wayne, State of Michigan, have invented a certain new and useful Improvement in Edge-Protectors for Concrete, and declare the following to be a full, clear, and exact description of the same, such as will enable others skilled in the art to 10 which it pertains to make and use the same, reference being had to the accompanying drawings, which form a part of this specification.

This invention relates to the reinforcement of curbing, and has for its object an improved means whereby the exposed edge of a concrete or artificial stone curb may be provided with a metal protector piece, which will receive and resist the impact of passing 20 wagon wheels, or even the slight, though steady, wear due to the passing of pedestrians.

In the drawings:—Figure 1, is a perspective of a section of curbing, the end of the 25 protector piece and of the concrete part being shown in section. Fig. 2, is a sectional elevation, on an enlarged scale, of the metallic reinforcing piece and a portion of the anchor piece. Fig. 3, is a perspective of the 30 head of an anchor piece. Fig. 4, is a sectional elevation of a slightly modified form of protector piece. Fig. 5, is an elevation of another modified form as respects the engagement of the anchor and protector pieces.

35 A represents the rising portion, and B the gutter portion of a section of concrete curbing, whose exposed upper edge is rounded, the immediate edge portion being finished by the curved top of protector piece C, whose 40 curvature is complementary to the desired contour of the edge as a whole. From the body portion of this protector piece, whose rounded upper surface constitutes this edge, extends a neck portion D, which terminates 45 in a claw portion E, which, extending much farther laterally than the neck portion D, serves in itself as an anchor of considerable holding power when embedded in concrete, which has been allowed to harden thereabout. In order, however, to avoid the possibility of an unusual impact tearing the entire protector piece away from its surrounding concrete, there is provided an anchor F having a flattened portion G, which, when 50 inserted within the claws E of the protector piece, easily engages therebetween, but

which, when turned through ninety degrees, engages with the edges of its flattened portion G very closely within the claws E of the protector piece; from its point of engagement at the upper end, it extends downwardly, first in an oblique direction, and then vertically toward the base of the curb, where it again bends and extends horizontally under the gutter portion. The exact route 60 traversed by the various portions of this anchor piece, with respect to the curb as a whole, is not material or specific, the idea being to afford, by its engagement through the concrete mass, a sufficient holding means 65 for the exposed protector piece.

In Fig. 4 is shown a slightly modified form of the protector piece in which in place of the claws E, the rear or inner portion of the protector piece is provided with fingers 75 K, which inclose a space of key-stone form into which a complementary anchor head M is adapted to be fitted in manner similar to what has already been described.

In the form illustrated in Fig. 5 the extreme inner end of the protector piece is solid and unbroken by a trough or keystone shaped edge, such as is illustrated in the other figures. Instead the neck part D is perforated at suitable intervals with holes 80 through which engages the anchor piece H, whose end J is first inserted when it and the adjacent portion of the branch L are nearly perpendicular to the side of the neck piece D. It is then turned so that the center portion 85 N engages through the hole and practically parallel with the axis of the hole, while the end J engages against the opposite face of the neck part D from that first approached by it; the branch L then extends 90 downwardly and into the body of the curbing as desired.

What I claim is:—

1. An edge protector for a curb, having, in combination with a rounded wearing surface, a neck portion adapted to extend inwardly into the concrete, and an anchor portion of greater diameter than the neck portion adapted, by engagement of the concrete thereabout, to hold the exposed wearing 100 surface of the protector in proper position with respect to the curb, and to be engaged interiorly by detachable anchor piece extending thereto from a remote part of the curb, substantially as described.

2. A metallic edge protector for a concrete curb and anchorage means therefor, com-

prising a unitary guard piece having a wearing surface, an attenuated neck portion and a securing portion at the inner end of said neck portion, and a crooked anchor piece adapted to be inserted in said securing portion and brought to an interlocking position with respect thereto, said piece extending from such point of engagement with the

guard piece into a remote portion of the curb, substantially as described.

In testimony whereof, I sign this specification in the presence of two witnesses.

EUGENE F. GLOCK.
